COLLAPSIBLE SHOWER

Arthur J. Sturwold, Chicago, Ill.

Application July 16, 1949, Serial No. 105,098

3 Claims. (Cl. 4—145)

1

This invention relates to a shower and more particularly to a collapsible shower and is particularly adapted for use in a trailer.

The use of trailers as abodes has become quite popular in recent years and the development of trailers and establishment of trailer camps supplying all the utilities has consequently been rapid. Because of the limited space in trailers however, bathing has been a difficult task for a trailer inhabitant. A bathtub is impracticable because it takes up too much room. A permanent shower room is feasible but the area it occupies is dead space as it is unused most of the time. Also such a shower room is usually unsightly. Use of a shower, furthermore, is often unsatisfactory because present day shower curtains are inadequate to prevent the water spray from escaping and damaging the furniture.

Thus one of the objects of this invention is to provide a collapsible shower which may be folded up and out of the way when not in use.

Another object of this invention is to provide a collapsible shower which may be quickly, easily and inexpensively installed, particularly in trailers.

Further objects and advantages of this invention will become apparent as the following description proceeds and the features of novelty which characterize this invention will be pointed out with particularity in the claims annexed to and forming a part of this specification.

A preferred embodiment of this invention is shown in the accompanying drawings in which:

Figure 1 is a partially broken away side view of the part of a trailer showing the general arrangement of the collapsible shower within the trailer.

Figure 2 is a sectional view taken on line 2—2 of Figure 1.

Figure 3 is a plan view taken on line 3—3 of Figure 2.

Figure 4 is a plan view of the top hanger rod which supports the shower curtain.

Figure 5 is a view taken on line 5—5 of Figure 3.

Figure 6 is a detail view showing a typical groove in the bar shown in Figure 4.

Figure 7 is a side view of the entire shower curtain unfolded.

Figure 8 is a top plan view of the entire shower curtain when folded.

Figure 9 is an enlarged view of a vertical cross section through the shower curtain.

Figure 10 is a partial view of the interior of the trailer showing the top hanger rod which supports the shower curtain, and the catch basin of the shower stall in the folded away position.

2

Referring to Figure 1, there is shown a trailer 11, in which is designated a roof or ceiling 12, a floor 13, and a wall 14. A shower head 15 is shown attached to ceiling 12 and supplied by fluid through hose 16. Fixedly fastened to ceiling 12 by brackets 17 is a continuous hanger rod 18 which is in spaced relation to the shower head 15. Hanging from rod 18 by means of hooks 19 is a shower curtain 20 which has a hem 21 in its upper end. Hem 21 has inserted therein a number of rods 22 to which are fastened hooks 19. The hooks emerge crosswise from the hem 21 through holes 23. The lower edge of curtain 20 is also provided with a hem 24 in which are also inserted a number of rods 25. Immediately adjacent and above the rods 25 in curtain 20 are a number of holes 26.

As shown in Figures 1, 2 and 3 there is supported on floor 13, beneath the shower head 15, a catch pan 27. Floor 13 has a drain 28 therein. Catch pan 27 has a drain spout 29 shown which is adapted to register with drain 28 in floor 13. Catch pan 27 is also hinged 30 along a portion of its edge to wall 14 and is provided with a clasp 31 for engaging a bracket 32, mounted on wall 14, when the catch pan 27 is swung out of position from the floor 13 against wall 14 so as to be stored. The catch pan in the stored away position is shown in Figure 10. There is also provided a number of horizontally extending and downwardly pointing fingers 33 attached to the inside vertical wall of the catch pan 27. A detail of the fingers is shown in Figure 5. These fingers engage curtain 20 through holes 26.

Figure 4 shows the continuous hanger rod 18 and the bracket 17. Rod 18 has grooves 34 at a plurality of points so as to engage hooks 19 by which shower curtain 20 is suspended. A detail of groove 34 is shown in Figure 6.

Figure 10 shows the catch pan 27 in the stowed away position and a means of sealing up drain 28 by use of a plug 35.

In operation the catch pan is released and lowered from the position shown in Figure 10. Plug 35 is removed and drain 29 enters and registers with drain 28. The shower curtain 20 is then unfolded and hooked in position on hanger rod 18. Then the lower end of the shower curtain is pulled until the fingers 33 enter holes 26 at the bottom end of curtain 20. This is possible because the shower curtain material is somewhat resilient. The catch pan 27 should be so fastened to wall 14 that the pan does not quite rest on the trailer floor, so that under the weight of the person showering the pan will descend a very small distance until it does rest on the floor.

The purpose for this is to make sure that the shower curtain is taut when in use as then there will be no folds or open spaces due to looseness in the curtain which will permit escape of the shower spray. It is pointed out that if the curtain is of the correct height initially, only a very small movement is necessary to make the curtain taut. The fingers 33 passing through holes 26 bear on rods 25 and therefore the load is evenly distributed by rods 25 along the length of the hem. The rods 18 at the top of the curtain serve the same purpose.

It can be seen that the hanger rod and the catch pan may be different shapes. When that is the case, the rods in the hems of the shower curtain can be made so that the contour of the shower curtain is approximately the same as that of the member to which the shower curtain is attached.

Thus it can be seen that I have provided a collapsible shower which can be easily folded up and stored away, which may be quickly, easily and inexpensively installed, which is easily adaptable to small enclosures where space is at a premium such as in trailers, and which provides an improved shower chamber for preventing leakage of the water spray.

While there has been shown and described a particular embodiment of this invention, it will be obvious to those skilled in the art that various changes and modifications can be made therein without departing from the invention and, therefore, it is aimed in the appended claims to cover all such changes and modifications as fall within the true spirit and scope of the invention.

I claim:

1. A collapsible shower chamber for use in a room having a floor, a ceiling, side walls, and a shower head affixed to the ceiling and supplied with fluid, comprising a hanger fastened to the ceiling of said room and in spaced relation to the shower head, said hanger being grooved at a plurality of points, a flexible shower curtain, a catch pan supported on the floor of said trailer, means for hanging said flexible shower curtain from said hanger, said means comprising a hem in the top edge of said shower curtain, a plurality of rigid bars inserted in said hem, a plurality of hooks attached to each rigid bar in the hem of said shower curtain and extending cross-wise through openings in said hem, said hooks being hooked over said hanger and in register with the grooves in said hanger, means for securing the bottom end of said shower curtain to the catch pan, and means for disposing of the fluid caught by said catch pan.

2. A collapsible shower chamber for use in a room having a floor, a ceiling, side walls, and a shower head affixed to the ceiling and supplied with fluid, comprising a hanger fastened to the ceiling of said room and in spaced relation to the shower head, a flexible shower curtain comprising a sheet of resilient waterproof material

hemmed at opposite edges to provide a plurality of hems in said curtain along its edges, a plurality of rigid bars inserted in each hem of said shower curtain, a plurality of hooks attached to each of the rigid bars in the top hem of said shower curtain and extending cross-wise through openings in said hem, said hooks being hooked over said hanger, the lower hem of said shower curtain being perforated to form a plurality of holes immediately adjacent and above the bars in said lower hem, a catch pan having a plurality of horizontally extending downwardly pointed fingers mounted on the inner vertical wall of said pan and being so positioned as to engage the holes immediately adjacent and above the bars in the lower hem of said shower curtain, a drain through the floor of said room, and a drain in said catch pan adapted to register with the drain in the floor of said room.

3. A collapsible shower chamber for use in a room having a floor, a ceiling, side walls, and a shower head affixed to the ceiling and supplied with fluid, comprising a hanger fastened to the ceiling of said room and in spaced relation to the shower head, said hanger being grooved at a plurality of points, a flexible shower curtain comprising a sheet of resilient waterproof material hemmed at opposite edges to provide a plurality of hems in said curtain along its edges, a plurality of hooks attached to each of the rigid bars in the top hem of said shower curtain and extending cross-wise through openings in said hem, said hooks being hooked over said hanger and in register with the grooves in said hanger, the lower hem of said shower curtain being perforated to form a plurality of holes immediately adjacent and above the bars in said lower hem, said bars in the top and lower hems of the shower curtain being of such length and shape as to approximate the contour of the bodies to which said hems are attached, a catch pan having a plurality of horizontally extending downwardly pointed fingers mounted on the inner vertical wall of said pan and being so positioned as to engage the holes immediately adjacent and above the bars in the lower hem of said shower curtain, a drain through the floor of said room, and a drain in said catch pan adapted to register with the drain in the floor of said room.

ARTHUR J. STURWOLD.
